UNITED STATES PATENT OFFICE.

ALBERT M. MUNZINGER, OF WILLIAMSPORT, PENNSYLVANIA.

BUNG-WITHDRAWING MACHINE.

1,057,492.

Specification of Letters Patent.

Patented Apr. 1, 1913.

Application filed December 22, 1908. Serial No. 468,801.

To all whom it may concern:

Be it known that I, ALBERT M. MUNZINGER, residing at Williamsport, in the county of Lycoming and State of Pennsylvania, have invented certain new and useful Improvements in Bung-Withdrawing Machines, of which the following is a specification.

My invention relates to a bung withdrawing machine, and has for its object the provision of a compact and effective machine for the purpose stated, which cuts through the bung progressively and removes it in a single operation. Bungs are ordinarily made of soft poplar wood highly compressed so that they expand after they have been tightly driven into the bung hole. Their removal is therefore difficult. Usually they are chipped out bit by bit, a tedious operation which also has the disadvantage that pieces of the bung may fall through the bung hole.

My machine has a slicing action and makes a helical cut through the bung while it is still in place, and then in the same operation by further rotation removes it, the bung, as it is raised out of the hole, ordinarily breaking and falling from the tool, but being in any case dislodged from the tool by the next bung removed. This disintegration is the result of the cutting into the bung and of the displacement of the material of the bung and its consequent weakening and further compression while it is still in position by the tool which is relatively large with reference to the bung. The expansion on the removal of the bung is the action obviously to be expected when the bung is no longer held together by the portion of the barrel surrounding it.

My invention consists in a bung extractor of the general nature illustrated in the drawings described in the specification, and more particularly pointed out in the appended 45 claims.

Referring to the drawings: Figure 1. is an elevation of my machine parts being shown in section. Fig. 2. is a side elevation, the tool being shown in a position slightly different from that illustrated in Fig. 1. Fig. 3. is a plan view of the device. Fig. 4. is a side elevation of a modification in which a motor together with reducing gearing is mounted on the tool support.

1 is a shaft which in the preferred form is flexible and is of any suitable structure.

This shaft is provided with a metal casing 2 on the end of which is screw threaded a support having legs 3, preferably three in number, which during the operation of the machine are designed to be drawn down upon the portion of the barrel adjacent the bung hole and for that purpose have beveled or slanted ends. The legs 3 are located symmetrically about the axis of the support 65 which is also the axis of the tool about to be described.

The shaft 1 is provided with a rotatable spindle 4 having a screw-threaded end onto which is adapted to be screwed tool 7. This 70 tool may of course be secured in any other suitable manner. Its upper end is close up against the metal casing 2 preventing upward motion of the tool with respect to the support. Downward motion is prevented 75 by the nut or collar 8 screwed onto the metal casing 2 above the support and projecting over the same.

The tool 7 is in the nature of an auger and is provided with a starting screw 9 80 or other centering means at its lower end and with a cutting up and removing helix 10 immediately above the starting screw. It does not, however, merely bore a hole through the bung but, as stated, slices 85 through it, the blade at the lower end of the helix lying in a plane intersecting at a sharp angle a plane at right angles to the axis of the helix adjacent said cutting blade. The parts sliced through are not 90 in that operation removed but the entire bung disintegrates when it has been removed from the bung hole. The exterior of the helix, as shown, is non-cutting. This helix for ease of operation, is preferably of uniform internal and external 95 diameter, that is, the auger, if solid would form a cylinder and, if the thread of the auger were removed, would likewise form a cylinder. However, while this is the preferred construction, it is not to be inferred that no other arrangement would be operative. The helix 10, as will shortly appear hereinafter, is in the nature of a slicer by reason of the construction of its lower end. 100 It is of low pitch and of considerable diameter extending well out toward the edge of the bung. The blade α at the lower end of the helix extends well out from the axis of the helix toward the edge of the bung 110 and is so located as to intersect at a sharp angle a plane at right angles to the axis

of the helix adjacent said cutting blade. The cutting blade thus enters the bung at a sharp angle to its surface and with a slicing action.

5 The legs 3 are of such length that the starting screw and auger have passed through the bung just before the ends of the legs rest upon the surface of the barrel. Once this relative position is reached fur-
10 ther rotation of the tool raises the bung out of the hole and, as above stated, the bung will ordinarily expand and break up so that it will fall in pieces from the tool automatically. However, should this action fail
15 to occur, the bung will be forced off when the next bung is removed.

Many bungs are made with the grain of the wood running substantially horizontal, and to such bungs my machine is peculiarly
20 applicable, since it acts substantially with the grain. After the starting screw has entered the bung, the sharp cutting edge at the lower end of the auger is forced into the top of the bung and the rotation of the tool
25 feeds it through the bung, cutting a helical path so that the machine progressively cuts through the bung while still in place and then removes it in a single operation.

30 The machine may obviously be driven by hand or by power. In Fig. 4 I have shown a compact form of the device in which a motor 12 is mounted co-axially with the tool and above it being supported by the legs 3. This motor may be of any desired nature
35 electrical or otherwise. Between the motor and the tool is a casing 13, containing reducing gearing 14 operatively connecting the motor with the tool.

40 It will be apparent that by this device bungs may be removed completely and expeditiously, and by a single operation.

What I claim as my invention is—

1. A bung withdrawing machine comprising a support, and slicing means rotatably mounted in said support and provided with 45 a helix having a non-cutting exterior and a slicing blade lying in a plane intersecting at a sharp angle a plane at right angles to the axis of the helix adjacent said cutting blade.

50 2. A bung withdrawing machine comprising a shaft, a support carried by said shaft adjacent its end, and adapted to be drawn down upon the barrel in the operation of the machine, and a slicing tool on the end 55 of said shaft provided with centering means and with a helix of low pitch and of much greater diameter than said centering means and having a transverse slicing edge extending well out from the axis of said helix and 60 located in a plane intersecting at a sharp angle a plane at right angles to the axis of the helix adjacent said cutting blade.

65 3. A bung withdrawing machine comprising a shaft, a support on said shaft adjacent its end and provided with symmetrically arranged legs, a spindle carried by said shaft and rotatable within said support, and a slicing tool of large size on said spindle provided with starting means and with a slicing device above the same having at its lower end a slicing blade extending well out from the axis of the helix and lying in a plane intersecting at a sharp angle a plane 75 at right angles to the axis of the helix adjacent said cutting blade.

Signed by me this 17th day of December, 1908.

ALBERT M. MUNZINGER.
